DUMP CAR CONSTRUCTION

Fred Hoelzgen, Saginaw, Mich.

Application August 21, 1944, Serial No. 550,391

3 Claims. (Cl. 105—253)

1

This invention relates to railway cars of the hopper-bottomed dump type, as commonly used for hauling and transporting coal. In the use of such cars experience proves that when the hopper doors are opened, a certain amount of coal immediately at the door opening will be discharged by gravity, but for the reason that the slope of the hopper bottom in the usual car of this type is not steep enough to cause the coal to slide out by gravity alone, the balance of the coal at the opening will jam up or arch over, which jam or arch must be broken up and the coal forming the same must be released and assisted down through the discharge hopper by inserting crow bars or other implements up through the open hopper doors and poking or raking the coal for breaking same loose. Furthermore such jams will be frequently repeated in the process of unloading a car. Another method of loosening such jams, as frequently resorted to, is to pound upon the sides of the car with hammers or other tools, and as these cars are generally constructed of sheet metal or steel, the result is that the cars are dented, pitted, scarred or stove in, and thus seriously damaged by such operations. On the other hand it is extremely inconvenient and dirty work for a man to get below an open hopper door for the purpose of inserting implements up through the same, for the purpose of loosening a coal jam or arch.

It is the primary purpose of the present invention therefore, to provide handy and convenient means, incorporated upon the car, for breaking up coal jams of the kind referred to, as same form at the hopper doors, and thus freeing the coal and facilitating its discharge through the hopper doors.

A further object of the invention is to provide a hopper-bottomed or dump type of railway car of the kind referred to, formed with tool ports or doors upon the sides thereof, and through which suitable tools or implements may be inserted for breaking up coal jams as formed therein in the process of unloading coal therefrom, and thus facilitating the unloading of the car.

A further object of the invention is to provide in a hopper bottomed or dump type of railway car of the kind referred to, the bottoms of the hoppers thereof sloping from either end of the car inwardly and downwardly towards the center thereof, the said hoppers being provided at their inner and lower ends with discharge doors hinged at their upper margins to the under side of the car body or frame, ovate openings, doors or ports formed through the sides of the car at each end

2

thereof, with the long axes of these doors or ports extended parallel with the slopes of the hopper bottoms at each end of the car, correspondingly shaped gates of larger superficial dimensions than the said ovate openings pivotally supported at one end to the margins of the upper ends of the said ovate openings and adapted to close downwardly thereover, and latches on the margins of the lower ends of the openings adapted to releasably engage the free ends of the gates in their closed positions.

A further object of the invention is to provide in a hopper bottomed or dump type of railway car of the kind referred to, the bottoms of the hoppers thereof sloping from either end of the car inwardly and downwardly towards their centrally located discharge doors, ovate ports, doors or openings formed through the sides of the car in spaced relation to the ends thereof with their long axes extended parallel with the slopes of the hopper bottoms, flat frames mounted over the outer sides of these ports or openings and secured to the margins thereof, the said frames being formed with ovate ports or openings axially aligned with the ports or openings through the sides of the car and with the margins of the ovate openings of the frame overlying the margins of the ovate openings through the sides of the car, ovately elongated gates of larger superficial dimensions than the openings of the frames, pivotally supported at one end to the margins of the upper ends of the openings of the frames and arranged to close by gravity downwardly thereover, and means at the lower ends of the openings to releasably engage the free ends of the gates in their closed positions.

With the stated objects in view, together with such other and additional objects and advantages as may appear from the specification and defined in the claims, attention is directed to the accompanying drawings as embodying preferred forms of the invention and preferred structural features thereof, and wherein:

Figure 1 is a fragmentary plan view of an end of a hopper bottomed or dump type of railway car of the kind referred to, the same being shown as positioned upon a section of railway.

Figure 2 is a side elevation of the assembly shown in Figure 1.

Figure 3 is a detail view on a greatly enlarged scale, showing a fragment of a side of a car of the type referred to, the same being formed with an ovately elongated port, door or opening in accordance with this invention, and being closable by means of a similarly shaped gate pivotally sup-

ported at one end to the upper end of the said opening in the side of the car.

Figure 4 is a section on the line 4—4 of Figure 3.

Figure 5 is a section on the line 5—5 of Figure 3.

Figure 6 is a section on the line 6—6 of Figure 3.

Figure 7 is a section on the line 7—7 of Figure 4.

Figure 8 is a view similar to that of Figure 3, showing in addition the employment of a flat frame or frames for positioning over the openings through the sides of the car, the frame being formed with a corresponding opening adapted to register therewith and carrying thereon the gate for closing over the said opening or openings as formed through the frames and the sides of the car.

Figure 9 is a section on the line 9—9 of Figure 8.

Figure 10 is a section on the line 10—10 of Figure 8.

This invention is designed for incorporation and use upon any conventional form or type of hopper railway car, such as the hopper-bottomed car shown generally at 5 in the drawings, and which includes the vertical sides 6 and ends 1, the medially disposed and horizontal bottom portion 8, the sloping hoppers 9 which slope inwardly and downwardly from each end 7 towards the medial floor portion 8 and below the same to form the discharge doors or openings 10, the hopper doors 11 hinged at their upper margins as at 12 transversely to the under sides of the medial floor 8 and at the ends thereof, the vertically and longitudinally extended reinforcing and dividing rib 13 which separate the transversely aligned discharge doors or openings 10, and which at their ends are angularly abutted against and joined to the sloping bottoms of the hoppers and to the sloping outer sides of the triangular shaped and transversely extended slide members 14, as indicated at 15, these members 14 being seated at the ends of the medial bottom or floor 8 and secured thereto in conventional manner.

In practising this invention and incorporating the same upon a hopper car of the type above described, ovately elongated openings, doors or ports 16 are formed through the sides 6 of the car in transverse alignment at each end thereof, medially of and slightly above the sloping bottoms 9 of the hoppers, and with the long or major axes of the openings extended in parallelism with the said sloping bottoms.

As shown in Figures 1 to 7, flat and ovately elongated gates 17 are provided, the same being of somewhat larger overall dimensions than the openings or ports 16 and so as marginally to overlap the same. These gates are pivotally secured at one end to the upper and outer ends of the margins of the ports 16, by means of bolts 18 passed outwardly through the said margins, the heads of the bolts being welded in place, and the threaded ends of the bolts passed freely through the ends of the gates as positioned over the outer sides of the said ports. Washers 19 are seated over the threaded outer ends of the bolts as passed through the ends of the gates, and lock nuts 20 are then turned down upon these threaded ends of the bolts. Thus the gates 17 may be pivotally closed down over the ports 16, or may be raised for opening the ports, as may be desired. In order to hold the gates closely and snugly closed over the ports, keepers 21 are welded or otherwise

seated upon the lower and inner margins of the ports 16, at the ends thereof, these keepers opening upwardly and being thus adapted for engaging the axially extended tabs 22 as integrally formed at the lower and inner ends of the gates 17. Finger holds or grips 23 are provided at the free ends of the gates 17 for facilitating raising or lowering the same. These holds or grips may be integrally formed from the stock of the gates 17 by merely folding up tab or ear portions thereof as cut from the stock, and as shown in Figure 5, or they may be separately formed and secured in place by rivets or other conventional manner. Similar keepers 24 are similarly secured upon the sides 6 of the car, upwardly above the margins of the upper and outer ends of the ports 16, and are located slightly outward of a vertical line passed through the pivot bolts 18. Thus these keepers 24 are adapted to slidably engage the tabs 22 at the free ends of the gates as same are raised and opened vertically, and owing to the positioning of the keepers 24 slightly outward of the vertical lines as passed through the opposite and pivoted ends of the gates, these gates will when thus raised, remain in their opened positions through gravity, but if they are inadvertently left open the jar and jerk of the car in starting will serve to jolt them free of the upper keepers 24, and they will then fall closed by gravity. In the construction described, the margins of the ports or openings 16 may be rounded off as indicated in the drawing, in order to facilitate the manipulation of tools and implements through these ports in manner later to be described, and if desired these margins may also be reinforced and strengthened in any conventional manner, as by collars (not shown) welded in place upon the inner faces of the said margins.

In the modified form of construction shown in Figures 8 to 10, the gates 17a instead of being pivotally mounted directly upon the sides of the car to close over the openings or ports 16a thereof, are mounted upon separate frames or collar members 26, which are in the form of flat and elongated plates. Complementary ports or openings 16b are formed in the lower and inner ends of these plates and are adapted to register with the ports 16a. But in forming these ports in the plates, they are made substantially smaller than the openings or ports through the sides of the car, thus providing overlapping margins which are then turned over inwardly, through the openings 16a, and are pressed down upon and around the margins of these openings at the inner sides thereof, as indicated at 26a, thus not only securely locking the frames or plates 26 in place but in addition providing thickened and nicely rounded margins at these openings for facilitating the working of tools and implements therethrough, in manner to be described. Before these frames are mounted upon the car however, the gates 17a are pivoted at one end by means of bolts 18a to the upper and outer margins of the ports 16b, in the same manner as for the previously described structures of Figures 1 to 7. Similarly keepers 21a and 24a are mounted upon the lower and upper ends respectively of the frames or plates 26, which are sufficiently elongated upwardly for the purpose, and these keepers are adapted to slidably engage the axially extended tabs 22a of the gates 17a, in the same manner and for the same purpose as heretofore pointed out in reference to the previously described structures. Likewise finger holds or grips 23a are formed or mounted upon the free ends of the gates 17a.

In the use of a hopper bottomed car of the type as described, or of any similar type, the gated openings or ports as described provide very handy and convenient means for access to the interior of the car, in the process of unloading coal or other loose materials therefrom, for the purpose of inserting crow bars or other implements through the openings for breaking up jams and arches as commonly form at the hopper doors of such cars in the process of unloading coal. The ovately elongated form of port or opening as here shown and described is thought to be the best form and best adapted for the purpose described, for the reason that such opening will permit the working and manipulation of tools or implements in every direction through the interior of the hopper, for the purpose of dislodging and breaking up jams or arches as above referred to. However any other form of port or opening through the side of the car might be employed and used, as thought desirable, without departing from the spirit of the invention. By providing the separate frame or plate for carrying the gate as pivotally mounted thereon, and the keepers and hand hold as mounted thereon, this equipment may be mounted upon any car, whether old or new, by merely cutting suitable ports or openings as described through the sides thereof to register with the openings of the frames. In such use the upper ends of the frames or plates may be spot welded to the sides of the car, the lower ends thereof being firmly locked in place through the expedient as described of turning the margins of the openings inwardly and down upon the inner faces of the margins of the openings through the sides of the car.

And while I have here shown and described certain embodiments of the invention, and specific structural features thereof, it is to be understood that the features as shown may be changed or modified as desired, within the scope of the claims.

I claim:

1. In a hopper car having a hopper therein sloping downwardly to a discharge door and having an ovately elongated tool passing port formed through the side of the car over the hopper thereof, the major axis of this port being extended in parallelism with the slope of the hopper bottom, a flat and elongated plate mounted over the outer side of the port, the inner and lower end of the plate being formed with a port therethrough in registry with the port of the car, and a closure element movably supported at one end upon the upper and outer end of the said plate and adapted to close downward over the ports of the plate and car.
2. In a structure according to claim 1, means upon the upper and outer end of the plate for releasably engaging the free end of the closure element when same is in raised position for opening the ports, and means for releasably latching the closure element in closed position.
3. In a hopper car formed with a hopper therein sloping downwardly to a discharge door and having an ovately elongated port formed through a side of the car over the hopper thereof, the major axis of the port being extended in substantial parallelism with the bottom of the hopper, a complementally elongated gate dimensioned to marginally overlap the margins of the port at the outer side thereof, the said gate being pivotally mounted at one end to the margin of the upper end of the said port, complemental latch members upon the opposite end of the gate and opposite end margin of the port for releasably holding the gate closed, a stop on the side of the car above the point of pivotal connection of the gate therewith and outwardly of a vertical line extended from said point of pivotal connection of the gate, said stop being arranged and adapted to engage the free end of the gate when raised vertically, to support the gate in opened position.

FRED HOELZGEN.
